United States Patent Office.

JOHN HEUERMANN, OF DAVENPORT, IOWA.

Letters Patent No. 66,961, dated July 23, 1867.

IMPROVED FIRE-ESCAPE.

The Schedule referred to in these Letters Patent and making part of the same.

TO ALL WHOM IT MAY CONCERN:

Be it known that I, JOHN HEUERMANN, of Davenport, in the county of Scott, and State of Iowa, have invented a new and improved Fire-Escape; and I do hereby declare that the following is a true and exact description thereof.

The nature of my invention consists in the construction and combination of two ladders and a fire-escape box in such manner as to admit of the raising and lowering of escape-box and one ladder, while the other ladder remains stationary; the attaching of a ladder to escape-box, as shown on drawings; the attaching of a cam in such manner as to throw such last-named ladder to and from the building by means of a rope connected therewith; the framing of such escape-box and escape-box ladder in such manner as to admit of folding up while not in use, and the connecting therewith arms or braces, as shown on drawings, for raising and holding such ladder in a firm position; reference being had to the accompanying drawings, making a part of this specification, in which—

Figure 1 is a perspective view, with fire-escape folded up.

Figure 2 is a perspective view, with fire-escape in position.

Figure 3 is a view of fire-escape box folded up, and

Figure 4 is a view of fire-escape box separate from the ladder.

Fire-escape box, fig. 4, is attached to ladder D by slides N, which box is raised and lowered by ropes R attached to roller A, from which the ropes R pass up and over the grooved wheels on iron shaft marked V, and the ends of rope are securely fastened to one of the bolts X which connect the frame of the escape-box, as shown on the drawings. Letter W represents the arms by which the ladder is raised from the ground and supported in its place. Letters E, F, G, and H represent the different pieces of iron frame of escape-box. Letter I, the floor of same, of wood or sheet iron. Letter L, of side pieces, of wood or sheet iron. Letter K, the ladder of escape-box. Letter J, the iron points or hooks of escape-box ladder. Letter C, the cam, by which escape-box ladder is moved to and from the building. Letter O represents an iron brace which is placed into grooves marked P to hold escape-box securely in shape when thrown open. Letter M represents the bottom batten or brace of iron, securely fastened by bolts, or otherwise, to frame-pieces F, so that the frame-pieces E of escape-box rest upon the bottom batten or brace when the escape-box is thrown open. The ladder of escape-box is securely fastened by iron bolts X to frame-pieces G and H, as shown on drawings. Letter Q represents the ropes by which the cam C is moved, so as to throw the escape-box ladder to and from the building. Letter B represents a ratchet for holding ratchet-wheel to its place. Letter S represents a ratchet-wheel securely fastened to roller A. Letter T represents a flange securely fastened to roller A. Letter U represents the chains securely fastened near the bottom of ladder D, which are to be used for fastening such ladder to its position on the ground. Letter Z represents the hole in roller A through which the ropes R pass and are securely fastened.

What I claim for my invention, and desire to secure by Letters Patent, is—

1. The combination and arrangement of the fire-escape box in all its parts, in the manner and for the purpose herein described.

2. The method of attachment of such fire-escape box to an ordinary ladder, in the manner and for the purpose herein described.

3. The method of attachment of the ladder to fire-escape box, so as to be easily thrown to and from the building by means of the cam and ropes, arranged substantially as and for the purposes set forth.

JOHN HEUERMANN.
